STEAM IRON HANDLE

Robert O. Ernest, Oak Park, Ill., and Richard E. Watson,
Detroit, Mich., assignors to Sunbeam Corporation, Chi-
cago, Ill., a corporation of Illinois

Filed Jan. 7, 1965, Ser. No. 83,329

Term of patent 14 years

(Cl. D49—6)

FIG. 1 is a perspective view of a steam iron handle embodying our design;

FIGS. 2, 3 and 4 are front, rear and side elevational views thereof, respectively; and

FIG. 5 is a top plan view thereof.

The dominant features of our design reside in the portions shown in full lines; the broken line showing of the base portion in FIG. 1 is for illustrative purposes only.

We claim:

The ornamental design for a steam iron handle, as shown and described.
